US00D922411S

(12) **United States Design Patent** (10) Patent No.: **US D922,411 S**
Kögler (45) Date of Patent: **** Jun. 15, 2021**

(54) **DISPLAY SCREEN OR PORTION THEREOF
WITH GRAPHICAL USER INTERFACE**

(71) Applicant: **VOLKSWAGEN
AKTIENGESELLSCHAFT,
Wolfsburg (DE)**

(72) Inventor: **Indra-Lena Kögler**, Wolfsburg (DE)

(73) Assignee: **VOLKSWAGEN
AKTIENGESELLSCHAFT,
Wolfsburg (DE)**

(**) Term: **15 Years**

(21) Appl. No.: **29/771,584**

(22) Filed: **Feb. 24, 2021**

Related U.S. Application Data

(62) Division of application No. 29/664,266, filed on Sep. 24, 2018, now Pat. No. Des. 914,696.

(30) **Foreign Application Priority Data**

Mar. 23, 2018 (DE) 40 2018 100 313.1

(57) **CLAIM**

The ornamental design for the display screen or portion thereof with graphical user interface, as shown and described.

DESCRIPTION

FIG. 1 is a front view of a display screen or portion thereof with graphical user interface showing my new design; and, FIG. 2 is a second embodiment thereof.

The broken lines showing a display screen illustrate portions of the article and form no part of the claimed design.

1 Claim, 1 Drawing Sheet
